(57) **CLAIM**

The ornamental design for the protective pad, as shown and described.

DESCRIPTION

FIG. 1 is a front view of a protective pad showing my new design;

FIG. 2 is a top plan view of the protective pad of FIG. 1;

FIG. 3 is a left side view of the protective pad of FIG. 1;

FIG. 4 is a right side view of the protective pad of FIG. 1;

FIG. 5 is a rear view of the protective pad of FIG. 1; and,

FIG. 6 is a bottom plan view of the protective pad of FIG. 1.

The intermittent line in the drawings represents stitching and forms part of the claim.
